KEY ACTUATED TYPE SELECTING MECHANISM

Thomas A. Keen, San Mateo, and James Kilburg, Redwood City, Calif., assignors, by direct and mesne assignments, of one-half to said Keen and one-half to Hannah M. Smith, Chicago, Ill.

Original application August 7, 1939, Serial No. 288,840. Divided and this application March 17, 1941, Serial No. 383,686

12 Claims. (Cl. 192—142)

This invention relates to key actuated type selecting mechanism, and particularly to mechanism of this kind which is suitable for use in a ticket printing and issuing machine of the kind customarily used for the sale of tickets representing wagers or entries in a race conducted under the so-called parimutuel system.

This application is a division of our co-pending application entitled "Ticket printing and issuing machine," filed August 7, 1939, Serial No. 288,840.

The machine disclosed in said co-pending application includes a ticket printing mechanism and keyboard controlled mechanism for selective setting of the type thereon and initiation of ticket printing and issuing operations of the machine. The keys of the machine are numbered to correspond with the numbers which identify the participants or entries in a race and depression of any one key effects setting of the printing mechanism and operation of the machine to print and issue a ticket bearing the number of the key depressed. It is to the mechanism through which the keys on the keyboard effect selective operation of the machine and to related mechanisms that the present application is particularly directed.

An object of the present invention is to provide mechanism for selecting type in a ticket printing machine or the like, which mechanism is controlled by a keyboard and in which depression of any key will effect motor driven operation of the selecting mechanism, with the work accomplished by the movement of the key itself reduced to a minimum and the heavier load of the actual type selection being carried by motor driven elements.

A further object of this invention is the provision in a key actuated type selecting mechanism of means to insure positive selection dependent upon key operation but motivated principally by a source of power which is brought into operative relationship with the selecting mechanism upon depression of the key.

A still further object is the provision of means through which depression of any key on the keyboard of a ticket printing machine will close an electric circuit to place the ticket printing mechanism in operation, together with means including a single switch which may be opened to disable or "scratch" all corresponding keys on a plurality of such machines.

Further objects and advantages of the invention are made apparent in the following specification, wherein reference is made to the accompanying drawings illustrating the invention in a preferred form.

In the drawings—

Fig. 1 is a side elevation of a ticket printing and issuing machine embodying the present invention, with parts of the machine broken away and parts shown in section for the purpose of clearly illustrating the principles of the invention;

Fig. 2 is a detail in side elevation of a portion of the selecting mechanism illustrated in Fig. 1;

Fig. 3 is a front elevation of the keyboard assembly illustrated in Fig. 1, with parts broken away;

Fig. 4 is a central vertical section of a key switch and housing therefor, one of which embraces a stem of each of the keys in the keyboard assembly;

Fig. 5 is a sectional view taken on the line V—V of Fig. 4;

Fig. 6 is a perspective view illustrating details of construction of a portion of the mechanism illustrated in Fig. 3; and

Fig. 7 is a similar view of a different portion of the mechanism.

The machine of which the present invention forms a part comprises, as is best illustrated in Fig. 1, a main housing 10 which encloses a type selecting mechanism controlled by the keys of a keyboard positioned adjacent the forward end of the housing, as well as the power transmission and other mechanisms incidental to the operation of the machine.

A cover member 11 disposed on top of the housing 10 encloses the major part of a ticket printing mechanism, and a motor housing 12 depending downwardly from the housing 10 contains a motor which supplies power for the ticket printing and issuing operation and which, through the present invention, also supplies the power required for the major portion of the type selecting operation which is effected by depression of a key.

The printing head which is disposed within the cover 11 comprises a plurality of discs with peripherally spaced type members. A strip to be printed upon, not shown in the present drawings, passes below the printing head, and a platen underlying the strip is swung upwardly during the printing operation to press the ticket strip against the lowermost type on the printing discs. These type discs, one of which is shown at 24, are supported by a rotatable shaft 17. A continuously operating motor 400 rotates a main drive shaft 333 through a sprocket 402, chain 403, and sprocket 405, and upon initiation of a ticket printing and issuing operation of the machine, a

of the printing head, first 360° or more in a forward direction and then in reverse to its original position. The type discs 24 are carried with the shaft 17, but being resiliently connected to it, their travel during the forward rotation may be interrupted to position any selected type face for printing upon the ticket. The resilient connection between the type discs and shafts 17 and the details of the power transmission which effects rotation of the shaft are not illustrated in the present application, as they do not form a part of the present invention and are all clearly shown and described in our co-pending application hereinbefore referred to.

The selection of the type face on the disc 24 is effected through keys 120 arranged in two banks adjacent the forward end of the machine and numbered to correspond to the numbering of the type on the disc 24. Assuming the disc 24 to be the one which prints the number of the entry upon which a bet is placed, the keys 120 are numbered, for example, from one to twelve to correspond to the numbers on those type faces, and depression of any key will result in printing of its corresponding number on a ticket. The mechanism which connects the keyboard with the entry disc 24 to effect printing of a number corresponding to the number of the key depressed is shown in Figs. 1, 2, 3 and 6. In Fig. 1 a selector plate 54 is shown as mounted on the printing head shaft 17 and as connected with the type disc 24 through a pin and slot connection 57. A selector finger 59 is carried by a block 121 mounted for sliding movement to and away from the axis of the selector plate 54 in a track 122. Consequently, the selector finger 59 may be advanced or retracted to register with any desired step in the helically stepped periphery of the selector plate 54. These steps are spaced radially to correspond to the spacing of the type faces on the disc 24 and are spaced progressively outwardly from the shaft 17 so that the distance of retraction of the finger 59 will determine the particular step to be engaged upon rotation of the selector plate. A lever 123 connects with the block 121 through a pin and slot connection 124. This lever is pivoted on a pin 125 carried by a bracket 126. At its lower end the lever 123 is pivoted, as shown, to the upwardly extending end 135 of a link 127. This end 135 of the link 127 is adjustably connected through a fitting 136, the purpose of which is to permit adjustment of the effective length of the lever and clamp it securely in its adjusted position. The opposite end of the link 127 is pivotally connected as at 128 to a lever 129. This lever 129 is keyed to a shaft 130 which, like an identical shaft 131, extends transversely of the machine. The shafts 130 and 131 are connected together to be oscillated simultaneously, as shown in Fig. 2, by a pair of levers 132 and 133 keyed to the shafts and connected at their lower ends by a link 134. Thus upon oscillation of either of the shafts 130 or 131 the lever 129 will be oscillated and, through the link 127 and lever 123, will cause the selector finger 59 to be advanced or retracted a distance depending upon the degree of oscillation of the shafts 130 and 131. These shafts are adapted to be oscillated by any one of the keys 120 and the degree of oscillation will depend upon the key depressed.

As will appear from the following description, the keys are so arranged that their depression is accomplished with but slight pressure of the finger, yet they serve positively to position parts of the mechanism which determine the setting of

the type during the power driven cycle of operation of the machine which follows the depression of any key.

The keys 120 are supported on shafts 140 which, as best shown in Fig. 4, are mounted for vertical reciprocation through a housing 200 which contains a spring 206 normally urging the keys to their raised position. Adjacent its lower end each of the posts 140 carries a projecting pin 151 (see Figs. 1 and 3) engageable with a lever 152 which will be swung downwardly on depression of any key. The lever 152 is fixed to a pivoted bushing 153 which also carries a downwardly extending lever 154, the construction of these parts being clearly shown in Fig. 6, so that the levers 152 and 154 function in the manner of a bell crank. Depression of any one of the keys 120 swings its associated lever 152 downwardly so that a pin 155 on said lever engages beneath a latch 156 on a latch bar 157. The latch bar 157 extends transversely of the keyboard and carries a latch 156 for each of the keys in the bank with which it is associated. The latch bar 157 is mounted on parallel links 158 and 159 which permit it to move to the side sufficiently for the pin 155 on any one of the key posts to engage under its corresponding latch 156. A spring 160 normally urges the latch bar to the right, as viewed in Fig. 3, and retains the pin 155 and its lever 152 in lowered position, after the pin has been engaged by the latch 156. This position is illustrated on the parts associated with the depressed key, shown in Fig. 3. The lever is held in this position until depression of another key serves to move the latch bar slightly to the left, thus effecting release of the lever 152 associated with the first key depressed and causes its own lever to become latched.

The levers 152 and 154 are swung in a counter-clockwise direction upon depression of the key against the tension of a torsion spring 161 (see Fig. 6) wound about the connecting bushing and normally urging them in the opposite direction. A pin 163 carried by the lower end of the lever 154 projects into a groove 164 (see Figs. 1 and 3) of a collar 165 which is slidable on a shaft 166 but splined against rotation on said shaft. Each of the collars 165 carries a cam 167 which, upon sliding movement of the collar to the right, which is effected by depression of the key which controls it, is moved into alignment with a cam lever 168 fixed to the shaft 130 or the shaft 131, as the case may be. There are, it should be understood, a pair of latch bars 157, one for each key bank, and these bars are connected together for simultaneous movement. Likewise there are two of the shafts 166 and every key in each bank controls a cam 167 on one of these shafts through mechanism identical with that just described.

The cam levers 168 which depend from the shafts 130 and 131 are identical, with the exception of that one shown at 129 in Fig. 1, which carries the pivot 128 at its lower end. The cams 167 are similar in shape but graduated in size. Their normal position is that shown in Fig. 1, with a flat side 169 registering with the lever 168.

Upon each ticket printing operation of the machine the shafts 166 are rotated through one complete revolution by the drive mechanism. Consequently, the cam 167 which has been selected and aligned by depression of a key with its lever 168 engages and swings that lever, imparting oscillation to the shafts 130 and 131, the degree of which oscillation depends upon the

size of the cam 167. As these cams are graduated in size corresponding to the number of the keys, the key depressed will determine the distance the selector finger 59 is advanced prior to the printing operation, and will further determine, through the selector plate 54, the type, face which is to be selected for printing.

The motor 400 from which the operating power of the machine is derived runs continuously, while the actual operation of the machine is controlled by a single cycle clutch, not shown, interposed between the motor and the power transmission. This clutch is controlled by a solenoid which, as fully disclosed in our co-pending application identified above, effects engagement of the clutch each time that it is energized to cause the machine to operate through a full cycle, imparting a complete rotation to each of the shafts 166 and also imparting the movement, heretofore described, to the printing head and printing action to the platen.

Depression of any one of the keys 120 effects closing of a circuit to the solenoid to initiate a ticket printing operation of the machine through a switch which forms a part of the key structure, as illustrated in Fig. 4, and which includes a pair of contact members 201 retained in place within the housing 200 by screws 202 which also function to clamp the ends of wires to the contact members, the wires forming a part of the switch circuit to the main clutch solenoid. The key post 140 carries a di-electric bushing 204 which supports a contact bridging member 205. Depression of the key against the tension of the spring 206 brings the bridge 205 into contact with the members 201 to close the circuit to the clutch solenoid.

The bridging member 205 is so spaced from the contact members 201 that it closes the circuit which initiates operation of the machine and causes rotation of the cams 167 just subsequent in time to the positioning of the cam selected by the key which has been depressed. This insures proper selection of the type to be printed before operation of the machine. Furthermore, the final downward movement of the key which closes the switch takes place after the key has been depressed to a point where the pin 155 on the lever 152 comes into position beneath the latch 156 on the latch bar 157. The spring 161 therefore raises the lever 152 and key to open circuit position, while the spring 206 within the key switch housing also tends to open the switch, although this latter spring is preferably not sufficiently strong to raise the key to its uppermost position. Through this arrangement the same key may be depressed to initiate successive ticket issuing operations of the machine without the necessity of releasing the lever 152 from its latched down position after each operation.

It is frequently desirable to put the machine through a trial operation to test electric circuits with which it may be connected and to test the adjustments of its ticket printing and issuing mechanisms. In order that a valid ticket may not be issued upon such trial operation, a special key is provided for the issuance of tickets bearing a symbol, such, for example, as a "T," in the normal place of the printed number indicating the number of the entry in a race. For a test or trial operation of the machine the selector mechanism remains in the position illustrated in Fig. 1, in which position the lowermost type on the type disc will be the one desired to be printed on the ticket to represent a trial operation. In

order to operate the machine without adjustment of the entry disc selector mechanism heretofore described so that the entry disc will function to print a "T" rather than an entry number on the trial ticket issued, a try key shown at 170 in Fig. 3 is employed. This key is mounted in the case in a manner similar to the keys 120 but has a post 171 which, as shown in Figs. 3 and 7, engages a vertically reciprocable slide 172 provided with slots 173 through which shoulder screws 174 extend to guide it for vertical sliding movement on a bearing bracket 175 which also serves as a bearing support for the shafts 130 and 131 and which supports a transversely extending plate 176 on which are formed bearings for the levers 152 and 154, hereinbefore described. The slide 172 has a rearwardly projecting arm 177 with vertical ears 178 at its opposite ends and a horizontal ear 179 intermediate its ends. Each of the ears 178 carries a pin 180 engageable with the extreme right-hand latch 156 of the latch bars 157. A spring 181 urges the slide upwardly and the lower end of the post 171 of the try key engages the ear 179 to depress the slide. Depression of the slide by the try key in this manner causes the pins 180 to latch beneath their associated latches 156 and in doing so to release the lever 152 of any other key which may have been depressed and latched down. Depression of the key 170 does not, however, adjust a cam to control the type disc. The key switch of the key 170, which is identical with that illustrated in Fig. 4, of course initiates a ticket printing and issuing operation of the machine in the usual manner but without effecting type selection, the result being that the normally lowermost type or character "T" on the type disc is printed on the trial ticket issued.

As heretofore set forth, the closing of the contacts caused by depression of any key effects energization of a clutch solenoid which causes engagement of a clutch to place the machine in operation to print and issue a ticket. The principal reason for providing individual switches for the several keys in order to energize the clutch solenoid is to permit of cancellation or "scratching" of keys bearing any one number throughout a plurality of machines. For example, the practice in using these ticket printing and issuing machines for the sale of tickets representing bets on horse races is to employ a plurality of machines for the sale of tickets for any given race. In the event that a horse originally scheduled to run in a particular race is not to run, the "scratching" of this horse is accomplished, with relation to the ticket printing and issuing machine, by rendering the corresponding keys on all machines inoperative. Consequently, if horse number "2" is not to run, key number "2" on all of the machines should be disabled in order to prevent accidental use and consequent sale of a void ticket. With the present structure, all of the keys bearing the same number on a plurality of machines may be in series circuit with a single scratching switch. Therefore, twelve "scratching" switches located in a suitable position, such as a main control room, will suffice to disable the keys bearing any single number on any number of machines. As the electrical circuit for accomplishing this "scratching" is conventional, and a typical wiring diagram is disclosed in our application, Serial No. 288,840, of which this application is a division, it is not disclosed in the present drawings.

Having thus described our invention, what we

claim and desire to secure by Letters Patent is:

1. A key-controlled differential mechanism comprising, a plurality of cams graduated in size and rotatable together upon a common shaft, a key associated one with each of said cams, a differentially movable member, cam followers carried by said member, and means whereby depression of any key will move its associated cam into position for engaging one of said followers to move said member.

2. A key-controlled differential mechanism comprising, a shaft, a plurality of cams graduated in size and splined to said shaft for rotation therewith and for sliding movement thereon, a differentially movable member, cam followers on said member engageable by said cams, a key associated with each cam, and means whereby depression of any key will effect rotation of the shaft and will slide its associated cam to a position for engagement with one of said followers. 20

3. A key-controlled differential mechanism comprising, a differentially movable member, a rotatable shaft, control mechanism for said member carried in part by said shaft and having elements slideable thereon, a key board, and means whereby depression of a key on said board will effect selection and sliding of one of the elements on said shaft to cause movement of said member corresponding to the key depressed. 25

4. A key-controlled differential mechanism comprising, a rotatable shaft, a differentially movable member carrying a plurality of cam followers, a plurality of cams graduated in size rotatable with and slideable on said shaft, a key board comprising depressible keys one for each of said cams, and a bell crank actuated by depression of each key and engaging its associated cam to slide it to a position for engagement with a follower on said member. 30

5. A key-controlled differential mechanism comprising, a shaft adapted to be rotated through a single cycle, a plurality of cams graduated in size rotatable with and slideable on said shaft, a differentially movable member, a plurality of cam followers on said member normally out of alignment with said cams, a board of depressible keys one for each of said cams, a bell crank actuated by depression of each key to engage its associated cam to slide it to a position of registry with one of said cam followers, and means for holding the cam in such position during the cycle of operation of the shaft. 40

6. A key-controlled differential mechanism comprising, a shaft adapted to be rotated through a single cycle, a plurality of cams graduated in size rotatable with and slideable on said shaft, a differentially movable member, a plurality of cam followers on said member normally out of alignment with said cams, a board of depressible keys one for each of said cams, a bell crank actu- 45

5 ated by depression of each key to engage its associated cam to slide it to a position of registry with one of said cam followers, and means for holding the cam in such position until depression of another key.

7. An electrically-powered key-controlled differential mechanism comprising, a switch for closing a circuit to said mechanism, members capable of being set to determine the magnitude of movement upon operation of the mechanism keys corresponding to said members, and means effective upon depression of a key to set its corresponding member and to close said switch.

8. An electrically-powered key-controlled differential mechanism comprising, a switch for closing a circuit to said mechanism, members capable of being set to determine the magnitude of movement upon operation of the mechanism, a keyboard having a key associated with each of said members and means effective upon partial depression of any one of said keys to set its associated members and effective upon complete depression thereof to close said switch.

9. An electrically-powered differential mechanism comprising, a key board, means associated with each key for setting a differential control mechanism to effect movement depending upon the key depressed, and a separate switch actuated by depression of each key to close an electric circuit controlling said mechanism.

10. An electrically-powered key-controlled differential mechanism comprising, a key board, differential controls adapted to be set by depression of any key on said board, and a separate switch enclosed in a housing surrounding each key stem and adapted to be closed by depression of the key for completing a circuit to the source of power for said mechanism.

11. An electrically-powered key-controlled differential mechanism comprising, a plurality of depressible keys each having a stem, a switch housing embracing each stem intermediate its ends and enclosing a switch for closing the control circuit upon depression of the key, and means engageable by the lower end of the stem which projects from said housing for setting a differential control member.

12. A key-controlled differential mechanism comprising, a differentially movable member, a plurality of cam followers on said member, a plurality of numbered keys, a rotating shaft, a cam slideable on said shaft and rotatable thereby for each of said keys, and means whereby depression of any key will effect sliding of its corresponding cam to a position for registry with one of said followers whereby said member will upon rotation of the shaft be moved a distance corresponding to the number of the key depressed.
